UNITED STATES PATENT OFFICE.

EROS V. BARKER, OF CELINA, OHIO.

BALING-PRESS.

1,111,819.

Specification of Letters Patent. Patented Sept. 29, 1914.

Application filed May 19, 1914. Serial No. 839,551.

To all whom it may concern:

Be it known that I, EROS V. BARKER, a citizen of the United States, residing at Celina, in the county of Mercer and State of Ohio, have invented a new and useful Baling-Press, of which the following is a specification.

This invention relates to baling presses of that type utilizing mechanism whereby binding wires or ties are placed about the bales to hold them under compression. In machines of this character it is desirable to have some means whereby there will be a pause in the compression of the bale during the positioning of a tie about the bale.

One of the objects of the present invention is to provide means whereby motion can be transmitted from a continuously rotating drive element to the follower, it being possible to uncouple said driving element from the follower and at the same time couple said element to needle operating means thus to enable the tie to be placed about and secured to the bale before the follower again proceeds to place material under compression.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown. In said drawings:—Figure 1 is a side elevation of a baling press embodying the present improvements, parts being broken away. Fig. 2 is a top plan view of the structure shown in Fig. 1. Fig. 3 is a bottom plan view. Fig. 4 is an enlarged vertical longitudinal section through a portion of the press and showing the means for connecting the drive element to the follower and to the needle operating bar. Fig. 5 is an enlarged section on line A—B Fig. 4. Fig. 6 is a detail view of a portion of the needle operating mechanism. Fig. 7 is an enlarged section on line C—D Fig. 2.

Referring to the figures by characters of reference 1 designates the base of the press on which is erected a press box 2 of the

usual or any preferred construction, this press box having a feed opening 3 in the top thereof and being provided with a follower 4 mounted for reciprocation.

Formed in the side walls of the press box 2 are needle receiving openings 5, the openings in each side wall registering with the corresponding openings in the opposed side wall. Guide arms 6 are extended outwardly from one of the side walls and at right angles thereto, these arms being formed with longitudinal grooves 7 which register with the adjacent openings 5 and constitute guides for straight needles 8 slidably mounted. The needles are connected, at their outer ends, by an integral upstanding rod 9. Braces 10 connect the outer ends of the arms 6 to one side of the press box and these braces constitute supports for a vertical shaft 11 journaled thereon. This shaft has an arm 12, one end of which is enlarged, as at 13 and formed with a longitudinal slot 14 through which the rod 9 extends loosely. Extending from the lower end of the shaft 11 is a short arm 15 having an upwardly extended forked end 16. Pivotedly connected to one side of this short arm 15 is an ear 17 extending from one end of an arcuate latch rod 18, said rod being extended through the fork 16 so as thus to be held against lateral movement relative to the arm 15, although permitted to swing upwardly and downwardly thereon. The latch rod 18 is extended under the press box 2 and through a guide bracket 19 secured to the bottom of the press box.

Journaled above the base 1 in suitable supports 20 provided therefor, is a shaft 21 to which is secured a gear 22 or other revolute drive element having a pitman 23 attached thereto. This pitman is connected to one end of a lever 24 fulcrumed on the base 1, the other end of the lever being extended through an opening 25 in the base 100 and having a link 26 attached to it. This link is connected to one end of a needle operating bar 27 which is slidably mounted in guide brackets 28 depending under the press box 2. This bar is disposed above the latch rod 18 and has a notch 29 in its lower face designed to be brought to position above the latch rod 18 during the reciprocation of the bar. The lever 24 has secured to it close to the pitman 23, a spring catch 30. The pivot 31 of the lever 24 also constitutes the pivot of a yoke 32 which extends under the upper

2
arm of said lever 24 and is connected, by a pitman 33, to the follower 4. The yoke 32 has a cross member 35 secured therein and provided with a depending lip 36. This lip 5 is so positioned that, when the upper portion of lever 24 is pressed downwardly onto the yoke 32, the catch 30 will spring into engagement with the lip 36, thus coupling lever 24 to the yoke 32 and causing 10 them to swing as one body about the pivot 31 during the actuation of the pitman 23. Thus, during this oscillation of the parts 24 and 32 about the pivot 31 the follower 4 will be reciprocated within the press box 2 and 15 any material in the path of the follower will be placed under compression. For the purpose of properly guiding the catch 30 into engagement with the lip 36, guide plates 37 are secured on the yoke 32 and upstand 20 therefrom so as to receive the lever 24 between them, as shown in Fig. 5.

Pivottally mounted on the base 1 is a lever 38 having a presser foot 39 connected to the inner end thereof and normally positioned 25 adjacent the path of the catch 30. The outer end of lever 38 is connected by a rod 40 to a releasing lever 41 mounted upon one side of the press box. Another rod 42 connects this lever to an arm 43 upstanding 30 from a shaft 44 mounted for rotation under the press box 2. This shaft 44 has a long lifting finger 45 extending therefrom and under the latch rod 18, said finger being preferably of spring metal and being normally positioned below and out of contact 35 with the latch rod 18, which rod normally rests in the bracket 19 below and out of contact with the bar 27.

Under ordinary conditions the lever 24 is 40 coupled to the yoke 32 in the manner hereinbefore described so that, during the rotation of the gear 22, the follower 4 will be reciprocated and any material supplied to the press box through the opening 3 will be 45 placed under compression. After a sufficient amount of material has been compressed to form a bale of the desired proportions, the operator pulls the lever 41 in the direction indicated by the arrow in Fig. 50 4 and this causes the rod 40 to push against the outer end of lever 38 and brings the presser foot 39 into position where it will be engaged by the lower end of the depending catch 30. Consequently said catch will be 55 uncoupled from the member 35 and during the next rotation of the gear 22, lever 24 will be raised and lowered about its pivot 31 while yoke 32 remains stationary upon the base 1 and follower 4 is held projected forward. It will be noted that when the yoke 60 32 is thus positioned on the base 1, the pitman 33 presses backwardly against the yoke and tends to bind said yoke more firmly upon the base 1, the parts thus forming a 65 lock to prevent the follower from springing

back under the pressure of the material under compression. When the lever 41 is shifted as designated by the arrow in Fig. 4, it also pulls on rod 42 and causes shaft 44 to rotate, thus to swing finger 45 upwardly and 70 to press the rod 18 yieldingly against the bottom of the bar 27. Consequently, during the oscillation of the lever 24 independently of yoke 32, bar 27 will be drawn rearwardly until the notch 29 arrives above the rod 18 75 whereupon said rod will be sprung up into the notch by the spring finger 45 and, during the return movement of the bar 27, the rod 18 will be actuated thereby and will cause the shaft 11 to rotate. Consequently 80 the arm 12 which is fixed to said shaft 11, will force the needles 8 longitudinally within the grooves 7 and transversely within the press box, these needles thus operating to engage the tie wires, indicated at W, and to 85 convey them across the press box to the gripping and twisting mechanism indicated generally at G and T. Inasmuch as the gripping and twisting mechanism constitutes no part of the present invention, it is not deemed necessary to enter into a detailed description or to illustrate the same other than in a general way.

During the completion of the rotation of the gear 22, the bar 27 will be drawn back to 90 its initial position, thus causing the needles to move back out of the press box. By the time the bar has returned to its initial position, lever 41 has been released, the foot 39 has been shifted out of catch engaging position, and finger 45 has been lowered so that, before the bar 27 can start upon its next stroke, the latch bar 18 will drop out of the notch 29. Furthermore, upon the completion 95 of the rotation of the gear 22, the catch 30 will engage the lip 36 on member 35, thus automatically coupling together the lever 24 and yoke 32 so that the operation hereinbefore described will be repeated.

110
What is claimed is:—

1. In a baling press, the combination with 115 a press box, a follower, and needles mounted for movement transversely of the press box, of a revoluble actuating element, a lever, a pitman connection between one end of the lever and said element, needle operating mechanism adapted to be actuated by said lever, an element mounted for oscillation, a pitman connection between said element and the follower, means for coupling said lever to said element, and means for simultaneously uncoupling said lever and element and coupling the needle operating mechanism to the lever.

2. In a baling press, the combination with 120 a press box, a follower, and a needle mounted for movement transversely of the press box, of a revoluble actuating element, a lever adapted to be oscillated thereby, mechanism operated by the lever and normally 125 130

uncoupled from the needle, an element mounted for oscillation, a pitman connection between said element and the follower, means normally coupling together said lever and element, and means under the control of an operator for simultaneously uncoupling said lever and element and coupling the lever to the needle.

3. In a baling press, the combination with a press box, a follower, and a needle movable transversely of the press box, of a continuously rotating drive element, a lever continuously actuated by said drive element, means normally coupled to the lever for transmitting motion to the follower, means normally uncoupled from the lever for actuating the needle, and means under the control of the operator for simultaneously uncoupling the follower actuating means from the lever and coupling the needle actuating means to the lever.

4. In a baling press, the combination with a press box, a follower, and a needle mounted for movement transversely of the press box, of a revoluble actuating element, a lever adapted to be continuously operated by said element, means normally coupled to and movable with the lever for actuating the follower, a coupling bar connected to and continuously reciprocated by the lever, a latch member connected to and movable with the lever, and means under the control of the operator for simultaneously uncoupling the lever from the follower actuating means and for shifting the latch member into engagement with the reciprocating bar.

5. In a baling press, the combination with a press box, a follower, and a needle mounted for movement transversely of the press box, of a revoluble actuating element, a lever adapted to be oscillated by said element, a member mounted to swing about the pivot of the lever, a connection between said member and the follower, means carried by the lever for automatically engaging said member to couple the lever and member together,

needle operating mechanism normally uncoupled from the needle, and means under the control of an operator for simultaneously coupling the needle operating mechanism to the lever and uncoupling the lever from said follower actuating member.

6. In a baling press, the combination with a press box, a follower, and a needle mounted to move transversely within the press box, of a lever, means for oscillating the lever, a member mounted to swing about the pivot of the lever and connected to the follower, a spring catch carried by the lever for coupling said member to the lever, needle operating mechanism normally uncoupled from the lever, a presser foot, and means under the control of an operator for simultaneously coupling the needle operating mechanism to the lever and shifting the presser foot against the catch to uncouple the lever from the follower actuating member.

7. In a baling press, the combination with a press box, a follower, and a needle mounted for movement transversely of the press box, of a lever mounted for oscillation, a notched bar mounted for reciprocation and connected to and actuated by the lever, a shaft, means operated by the shaft for shifting the needle, a latch rod connected to the shaft and extending radially therefrom and under the notched bar, a resilient lifting finger extending under the latch rod, a lever under the control of an operator, and means operated by said lever for pressing the yielding finger against the latch rod to force the rod into the notch in the reciprocating bar, thereby to couple the first named lever to the needle.

In testimony that I claim the foregoing as my own, I have hereto affixed my signature in the presence of two witnesses.

EROS V. BARKER.
